UNITED STATES PATENT OFFICE.

GEORGE V. A. BROWN, OF CHICAGO, ILLINOIS.

POCKET-BOOK HOLDER.

1,121,465.

Specification of Letters Patent. Patented Dec. 15, 1914.

Application filed April 28, 1914. Serial No. 835,008.

To all whom it may concern:

Be it known that I, GEORGE V. A. BROWN, a subject of the King of Great Britain, residing at Chicago, in the county of Cook 5 and State of Illinois, have invented new and useful Improvements in Pocket-Book Holders, of which the following is a specification.

The invention relates to an improvement 10 in holders for pocket-books and the like, comprehending specifically a structure adapted to be removably engaged with the article to be secured with the parts thereof arranged to coöperate with the pocket to 15 prevent the unauthorized abstraction of the article from the pocket.

The main object of the present invention is the provision of a holder including spring elements adapted to receive and frictionally 20 engage a pocket-book or similar article and provided with pocket engaging member arranged to coöperate with a portion of the pocket to limit the movement of the device longitudinally of the pocket, whereby to prevent 25 unauthorized abstraction of the article.

The invention in the preferred form of details will be described in the following specification, reference being had particularly to the accompanying drawings, in 30 which:—

Figure 1 is a view in elevation illustrating the application and use of the improvement. Fig. 2 is an edge view of the holder. Fig. 3 is a top edge view of the same.

The improved holder comprises an article 35 engaging member constructed preferably of a single piece of material formed to provide a rectangular outline including upper and lower bars 1 and 2, and side bars 3. The upper and lower bars 1 and 2 are extended 40 beyond one of the side bars 3 to form projections 4, and in completing the engaging element, that is projected portions are formed in return bends to provide spaced 45 members disposed in parallel relation with the upper and lower bars 1 and 2. The character of the material and the form of the return bend, as illustrated, constitute the bars 1 and 3 and 2 and 4, as spring clamps, 50 serving to frictionally engage and secure the article therebetween, as will be apparent from the drawings.

Pivotedly connected at the juncture of the side bars 3 with the lower bar 2 are holding

rods 5 terminating at their upper free ends 55 in inturned hook portions 6. The bars 5 are preferably round and gradually tapered from their pivotally connected terminals to their free ends. A spring 7 is arranged intermediate the bars 5, said spring having 60 sufficient tension to spread the hook ends of the holding bars beyond the engaging member. Spring clips 8 are secured upon the upper bar 1 of the engaging member and serve to provide means to frictionally hold 65 the bars 5 in approximate parallelism with the side bars 3 when it is desired to secure the holding bars in inoperative position.

In use, the article to be secured such as pocket-book indicated by dotted line 9 is 70 passed between the clamping bars previously described, and the article with the attached holder placed in the pocket as 10. Upon release of the downward pressure upon said article, the holding bars under the influence 75 of the spring 7 move outwardly so that their upper ends rest in engagement with the side edges of the pockets. Any attempt to abstract the article while the holder is in this condition will cause the hook terminals 6 of 80 the arms 5 to engage the upper edge of the pocket in either side of the entrance opening, locking the article against abstraction. When authorized abstraction of the article is desired, the holding bars 5 are moved in- 85 wardly and engage beneath the clips 8, whereupon the article and holder may be readily removed.

The improved holder is constructed entirely of metal, and is adapted in any one 90 particular form to coöperate with a variety of articles. This is thoroughly effective in preventing unauthorized abstraction of such articles and in its effectiveness will not mar the article or pocket.

95 What is claimed is:—

1. A pocket book holder comprising spaced article engaging members, holding arms pivotally connected thereto and formed at their upper ends to provide hooks, and 100 a spring for normally spreading said arms.

2. A pocket book holder comprising spaced article engaging members, holding arms pivotally connected thereto and formed at their upper ends to provide hooks, a 105 spring for normally spreading said arms, and clips carried by the engaging member to hold said arms in inoperative position.

3. A pocket book holder comprising spaced article engaging members, holding arms pivotally connected thereto and formed at their upper ends to provide hooks, and a spring for normally spreading said arms, said article engaging members being integrally connected.

In testimony whereof I affix my signature in presence of two witnesses.

GEORGE V. A. BROWN.
